UNITED STATES PATENT OFFICE.

FRANK BURNS, OF WESTFIELD, NEW YORK.

CATCH.

1,300,570.

Specification of Letters Patent. Patented Apr. 15, 1919.

Application filed May 18, 1918. Serial No. 235,312.

To all whom it may concern:

Be it known that I, FRANK BURNS, a citizen of the United States, residing at Westfield, in the county of Chautauqua and State 5 of New York, have invented certain new and Useful Improvements in Catches, of which the following is a specification.

This invention relates to certain new and useful improvements in catches or latches or 10 fastening devices for boxes, trunks or other receptacles or articles and it has for its objects among others to provide a simple, cheap yet efficient and reliable catch or latch so constructed as not to present any protruding 15 parts, the same being designed to be set in flush with the face of the box or other article to which it is applied.

It has for a further object to provide a device of this character capable of manufacture at small cost, not liable to injury or to 20 get out of order and one in which the parts shall be automatically drawn together and locked in position and securely held against accidental separation.

25 I aim further at improvements in the details of construction whereby the above-named results are obtained and the latch members readily assembled and the device as a whole applied in position by unskilled 30 labor.

Other objects and advantages of the invention will hereinafter appear and the novel features thereof will be particularly pointed out in the appended claims.

35 The invention is clearly illustrated in the accompanying drawings, which, with the numerals of reference marked thereon, form a part of this specification, and in which—

Figure 1 is a rear elevation of one form 40 of my improvement with a portion broken away and shown in section.

Fig. 2 is a section on the line 2—2 of Fig. 1, looking in the direction of the arrows.

45 Fig. 3 is a view looking at the bolt-receiving edge of the main portion of the latch.

Fig. 4 is a rear elevation of a modified form.

50 Fig. 5 is an edge view of the same.

Fig. 6 is a detail in elevation of a modified form of bolt member.

Like numerals of reference indicate like parts throughout the different views.

55 Referring first to Figs. 1, 2 and 3, 1 designates the body portion of the device which

may assume any desired contour having holes 2 for the reception of the screws or other means by which it is secured in position upon the box or other receptacle. It 60 has a cut-away portion or opening 3 from one side of which extends the member 4 at substantially right angles to the body portion 1 and this portion 4 has a slot 5 through which passes the lever 6 and in which it has 65 limited movement.

The body portion 1 has, at what may be best termed its upper edge, the right-angled extension 7 in which is provided an opening 8 of substantially key-hole form, as seen 70 best in Fig. 3.

The lever 6 is mounted upon a stud or pin 8 which, in the present instance, is shown as having at one end a head 10 with a slot 11, somewhat similar to a screw, the other end 75 being reduced, as seen at 12, and riveted within a countersink 13 in the body portion 1, as seen clearly in Fig. 2. This countersunk portion serves as a washer. Other forms of means may be provided, however, 80 for mounting the lever.

The lever is extended in the form of a yoke 14, as seen best in Fig. 2, both ends of the yoke being enlarged, as seen at 15, and mounted upon the member 9. 85

16 is a spring encircling the member 9 between the side members of the yoke, with one end bearing against the lateral portion 4, as seen at 17 in Figs. 1 and 2, and the other end bearing against the cross member 18 of 90 the yoke, as seen at 19 in said Figs. 1 and 2. The spring thus tends to normally force the yoke in the direction indicated by the arrow a in Fig. 1.

20 is a plate designed to be secured by 95 screws or other means to the under side of the top of the box or trunk or other receptacle and having depending therefrom a stud or bolt 21, as seen clearly in Fig. 1, the free end of which is made conical, as seen 100 at 22, which serves to center the bolt member as the lid is brought to its closed position. Projecting laterally from the bolt member 21 is the lug 23, the upper face of which is slightly inclined or rounded, as 105 shown at 24, for a purpose which will soon be made clear.

In use, the member 1 being affixed to the box or other receptacle within a chamber or recess provided therefor so as to receive the 110 member 4 and the lever and yoke, and the member 20 being applied to the under side

- of the top of the receptacle, when the top or lid is closed the bolt member 21 enters the opening 8 in the face member 7 and, by reason of its conical end 22, is automatically centered, the lug 23 entering the portion 8^a of the slot. The under beveled face 25 of the lug or projection 23 engaging the edge of the cross member of the yoke forces the same to one side, against the tension of the 10 spring, until the lug or projection passes said cross portion of the yoke when the spring forces the yoke over the upper edge of the lug or projection and, by reason of the rounded or inclined upper face of the 15 lug, the yoke riding thereupon serves to automatically draw the bolt and, consequently, the top or lid of the receptacle down snugly upon the receptacle and the spring acts to keep the parts firmly in close engagement 20 and avoids any possibility of accidental separation of the parts. When it is desired to open the lid, all that it is necessary to do is to reach through the opening 3 with the thumb or finger and move the latch 6 in the 25 direction of the arrow 6 in Fig. 1, when the cross portion of the yoke is moved out of engagement with the lug or projection 23 and the lid is free to be moved into open position.
- 30 In Fig. 4 I have shown a device embodying all of the essentials of the form just described and operating in the same way except that the lever 26 is arranged at right angles to the yoke 27, as clearly indicated 35 in said figure, the other parts being the same, the only difference being that in actuating the lever to disengage its yoke from the lug on the bolt, the lever is moved downward in the direction of the arrow seen in 40 Fig. 4, and the member 28, which corresponds to the member 4 in Fig. 1, is disposed parallel with the yoke instead of at right angles thereto. One end of the spring 16 bears against the member 28 and the 45 other against the cross portion 29 of the yoke. In all essentials, however, the construction is the same, both as to the disposition of the parts and the mode of operation except that, as above stated, in this latter form, Fig. 4, the lever is disposed at right angles to the yoke and to the bolt instead of all three of these members being substantially in parallel relation.
- 50 In some instances I may construct the member 20 with a right-angled face member 30, as seen in Fig. 5, which serves to strengthen the same and which will be set into the edge of the cover, as will be readily understood.
- 60 In some cases I may construct the bolt member carried by the member 20 as seen in Fig. 6, wherein said bolt member 31 has the conical end 32 serving to center the bolt, as in the forms shown in Figs. 1, 2 and 4, 65 but, instead of having the lateral lug or

projection, I form the bolt adjacent the member 20 with a cut-away portion 33 forming a shoulder 34 against which the cross member of the yoke engages as the cover is closed.

70 From the foregoing, it will be seen that I have devised a simple, efficient and durable and reliable form of catch for the purposes stated and, while the structural embodiment of the invention as herein disclosed is what 75 I at the present time consider preferable, it is evident that the same is subject to changes, variations and modifications in details, proportions and relative arrangement of parts, without departing from the spirit of the invention or sacrificing any of its advantages. I, therefore, do not intend to restrict myself to the details hereinafter disclosed, but reserve the right to make such changes, variations and modifications as come properly within the scope 80 of the appended claims.

85 What is claimed as new is:—

1. A catch comprising a body portion, a spring-actuated angled member and an operating member mounted on a common pivot, and a relatively-movable member provided with a bolt portion movable at right angles to the pivot of said lever and interlockable with and adapted for coöperation with and 90 endwise movement by the cross portion of the angular member, said body portion having an opening through which the said lever is accessible for operation, and the lever being disposed entirely behind said body portion.

95 2. A catch comprising a body portion with an opening and lateral lug with slot, a combined actuating lever and bolt-engaging member pivoted in said body portion with the lever extended through said slot and accessible through said opening, a spring bearing against said lug and against the bolt-engaging member, and a bolt movable at right angles to the pivot of said bolt-engaging member and engageable with the latter, the said lever being disposed in its 105 entirely behind the said body portion and protected thereby.

110 3. A catch comprising a body portion with opening and lateral lug with slot, a combined yoke and actuating lever pivoted in said body portion with the lever extended through said slot, a spring bearing against said lug and against the cross portion of the yoke, and a bolt movable at right angles to the pivot of the yoke and engageable with the cross portion thereof, said bolt having a lug projecting outwardly to engage the 115 said cross portion.

120 4. A catch comprising a body portion with opening and lateral lug with slot, a combined yoke and actuating lever pivoted in said body portion with the lever extended through said slot, a spring bearing against 125 said lug and against the cross portion of the yoke, and a bolt movable at right angles to the pivot of the yoke and engageable with the cross portion thereof, said bolt having a lug projecting outwardly to engage the 130

said lug and against the cross portion of the yoke, and a bolt movable at right angles to the pivot of the yoke and engageable with the cross portion thereof, said bolt having a lug projecting outwardly to engage the said cross portion, and inclined upon its outer face.

5. A catch comprising a body portion having an opening and a lateral member, a lever pivotally mounted on the body portion and movable through said member and accessible through said opening, a yoke mounted on the pivot of and movable with the lever and a spring acting on the yoke to normally hold it in engagement with a cooperating bolt, combined with a member having a bolt portion with lateral lug adapted to interlock with the cross member of the yoke, and conical end serving as a centering means.

6. A catch comprising a body portion having an opening and a lateral member, a lever pivotally mounted on the body portion and

movable through said member and accessible through said opening, a yoke movable with the lever and a spring acting on the yoke to normally hold it in engagement with a cooperating bolt, combined with a member having a bolt portion with lateral lug adapted to interlock with the cross member of the yoke and conical end serving as a centering means, the upper face of said lug being inclined for coöperation with the cross portion of the yoke.

7. A catch comprising a body portion having a countersunk opening, a lever, and a pivot for the lever having one end riveted in the countersunk opening, the countersunk portion serving as a washer.

In testimony whereof I affix my signature in the presence of two witnesses.

FRANK BURNS.
